UNITED STATES PATENT OFFICE.

JOHN FOLLANSBEE, OF PITTSBURG, PENNSYLVANIA.

WEATHER-STRIP.

SPECIFICATION forming part of Letters Patent No. 604,676, dated May 24, 1898.

Application filed December 23, 1897. Serial No. 663,129. (No model.)

To all whom it may concern:

Be it known that I, JOHN FOLLANSBEE, a citizen of the United States of America, residing at Pittsburg, in the county of Allegheny and State of Pennsylvania, have invented certain new and useful Improvements in Weather-Strips, of which the following is a specification, reference being had therein to the accompanying drawings.

10 This invention relates to certain new and useful improvements in weather-strips, and relates particularly to that class adapted for use on windows fitted with sliding sashes, and aims to provide a strip for this purpose that will effectually form a weather-proof joint between the sash and its jamb.

15 The invention further aims to provide a weather-strip of this nature that may be readily applied to the side rails, the upper and bottom rails, and to the meeting-rails of the sash; and to this end the invention consists in the novel construction and arrangement to be hereinafter more specifically described, and particularly pointed out in the claims.

20 25 In describing the invention in detail reference is had to the accompanying drawings, forming a part of this specification, and wherein like letters of reference indicate similar parts throughout the several views, in

30 which—
Figure 1 is a perspective view of a portion of a window frame or jamb with my improved strip in position. Fig. 2 is a similar view of a portion of a window, showing weather-strip on the sash-rail. Fig. 3 is a horizontal sectional view of one side of the frame and a portion of the sash. Fig. 4 is a perspective view of a portion of the sash-strip. Fig. 5 is a similar view of the frame-strip. Fig. 6 is a vertical sectional view of a portion of the two sashes, showing the construction of the strip as applied to the meeting-rails. Fig. 7 is a perspective view of a portion of the frame, showing the arrangement of the strip in the base 35 of said frame. Fig. 8 is a transverse sectional view of the base of the frame and a portion of the sash, also showing a portion of the inner face of the frame in side elevation. Figs. 40 45 50 55 60 65 70 75 80 85 90 95 100 9 and 10 are perspective views of the strip as arranged for meeting-rails.

Referring now to the drawings by reference-

letters, *a* represents one of the sliding sashes, and *b* the casing or frame which receives the said sash, the said frame being provided with an ordinary groove *c* on its inner face. The 55 sash-rail *a* is tenoned along its engaging face, so that the two side faces of the weather-strip will be exactly flush with the side faces of the sash when the said strip is in its position on the sash. The strip is composed of two sections, 60 one of which is arranged within the groove *c* on the frame or casing and the other of which is secured to the engaging face of the sash, the two sections being adapted to match perfectly together. Each section is composed, preferably, of metal, and I will now describe the strip which is attached to the rail of the sash. This strip is formed by bending pieces of zinc or other suitable metal, as shown in Fig. 4 of the drawings, making the same practically U- 70 shaped in form, and providing a flat web or base *d*, which is provided throughout with suitable apertures *d'* for the reception of the screws *d*², which fasten the strip securely to the sash. This strip is bent at right angles to the 75 web or base *d*, forming the inwardly-projecting flange *e*, and is then returned upon itself to form the outwardly-projecting flange *e'*, the edge of which is perfectly flush with the web or base *d*. This bending of the strip upon itself forms a pocket or space *e*² between the 80 projecting ribs or flanges *e* and *e'* that is adapted to receive the projecting ribs or flanges that are formed upon that section of the strip that is affixed to the casing or frame, 85 and which I will now describe. This latter strip is likewise composed of a suitable piece of zinc or other metal formed into the web or base *f*, which, like the strip secured to the sash-rail, is provided with suitable apertures 90 *f'* to receive the fastening-screws *f*² for affixing the same to the casing or frame. The edges of this strip are each bent in the same direction—at right angles to the web or base *f*—thereby forming the projecting ribs or 95 flanges *g*, which engage in the groove or receptacle *e*² provided therefor in the strip that is secured to the sash-rail, the said projecting ribs or flanges sliding neatly within said grooves as the sashes are raised or lowered. 100

In Figs. 6, 7, 8, 9, and 10 I have shown the same principle as heretofore described ap-

plied to the base and top of the window and to the two meeting-rails. In this construction the strip that is affixed to the sash is countersunk therein and secured in the same 5 manner as heretofore described by screws h through the apertures h' provided therefor in the web h^2 , one edge of said web being bent at right angles to the web to form the projecting flange or rib h^3 , which engages in the 10 groove k^3 provided therefor in the strip which is affixed in the base k of the frame or the top of the frame, as the case may be. This latter strip is likewise composed of the base or web k' , provided with apertures k^2 for the reception 15 of the fastening-screws and having its one edge bent at right angles to the said base and returned upon itself, so that the edge of the strip will be flush with the base, and thereby forming the projecting ribs or flanges k^4 20 and k^5 , as well as the grooves k^3 , as heretofore stated. The strip for the one meeting-rail is exactly similar in form and the strip for the engaging meeting-rail may also be similar or may be slightly varied, as is shown 25 in Fig. 6, the upwardly-projecting flange being slightly shorter, though I do not wish to limit myself to this particular form of construction, as this strip may be of the same design as is shown in Fig. 10, as will be readily apparent.

By thus forming the weather-strip it will be observed that a double guard is provided, through the arrangement of the projecting ribs or flanges, that will effectually exclude 35 rain, snow, or dust from passing between the sash and its frame or casing without in any manner interfering with the easy operation of the sashes.

In practice these metallic strips may be 40 manufactured in suitable lengths which can be cut by the purchaser to the right size to fit the windows for which they are intended and may be readily applied by any person

of ordinary intelligence without the aid of skilled labor.

Although the strip is shown and described herein specifically to windows, yet it will readily be observed that the same principle may be applied to doors in many instances, the principle of construction being retained.

Although the foregoing appears to embody the preferred form of my invention, yet I do not wish to limit myself specifically thereto, as various slight changes may be made in the details of construction without departing 55 from the general spirit of my invention.

Having fully described my invention, what I claim as new, and desire to secure by Letters Patent, is—

1. A weather-strip comprising two metallic 60 strips, one of which is formed of a flat base or web, with a longitudinally-raised portion bent upon itself and extending at right angles thereto at each edge of the base, and thereby providing recesses or grooves for the reception 65 of two projecting ribs or flanges formed on each edge of a similar base or web, substantially as shown and described.

2. A weather-strip comprising two sections, each of which consists of a metallic strip having a flat base provided throughout with apertures, one of said strips being formed at its edge with a longitudinally-raised portion forming a projecting rib, and the other of which is formed at its edge with a similar 75 longitudinally-raised portion that is bent upon itself to receive the projecting rib of the engaging strip, substantially as shown and described.

In testimony whereof I affix my signature 80 in presence of two witnesses.

JOHN FOLLANSBEE.
